CLAIM

The ornamental design for a sports bottle cap, as shown and described.

DESCRIPTION

FIG. 1 is a front, right, top perspective view of a sports bottle cap, showing my new design in a first configuration for use with the spout folded and the handle positioned vertically; FIG. 2 is a front, right, bottom perspective view thereof; FIG. 3 is a top plan view thereof;

FIG. 4 is a right side elevation view thereof;

FIG. 5 is a front elevation view thereof;

FIG. 6 is a rear elevation view thereof;

FIG. 7 is a left side elevation view thereof;

FIG. 8 is a bottom plan view thereof;

FIG. 9 is a front, right, top perspective view of the sports bottle cap of FIG. 1, shown in a second configuration of use with the spout extended and the handle positioned to the rear of the cap;

FIG. 10 is a front, right, bottom perspective view;

FIG. 11 is a top plan view thereof;

FIG. 12 is a right side elevation view;

FIG. 13 is a front elevation view;

FIG. 14 is a rear elevation view thereof;

FIG. 15 is a left side elevation view; and,

FIG. 16 is a bottom plan view thereof.

The equal-length broken lines in the drawings depict portions of the sports bottle cap that form no part of the claimed design.
